CLAIM

The ornamental design for a boat lift motor and gear housing, as shown and described.

DESCRIPTION

FIG. 1 is a rear perspective view of a boat lift motor and gear housing showing our new design;

FIG. 2 is a side elevational view thereof, shown at a slightly enlarged scale;

FIG. 3 is a side elevational view opposite that shown in FIG. 2;

FIG. 4 is a rear elevational view thereof, shown at a slightly enlarged scale;

FIG. 5 is a front elevational view thereof, shown at a slightly enlarged scale;

FIG. 6 is a top plan view thereof, shown at a slightly enlarged scale; and,

FIG. 7 is a bottom plan view thereof, shown at a slightly enlarged scale.

The broken line showing of environmental structure is for illustrative purposes only and forms no part of the claimed design.
